UNITED STATES PATENT OFFICE.

CHASE KEHRER, OF PERTH AMBOY, NEW JERSEY.

IGNITION APPARATUS.

1,396,637.

Specification of Letters Patent.

Patented Nov. 8, 1921.

Application filed July 25, 1919. Serial No. 313,166.

To all whom it may concern:

Be it known that I, CHASE KEHRER, a citizen of the United States, residing at Perth Amboy, in the county of Middlesex and State of New Jersey, have invented new and useful Improvements in Ignition Apparatus, of which the following is a specification.

This invention relates to improvements in distributors for use on motor vehicles and more particularly to a distributor designed for use on Ford automobiles which will supplant the ordinary timer and eliminate the necessity of using more than a single induction coil for ignition purposes.

Heretofore, the ignition system of Ford automobiles included a timer mounted on the cam shaft through which the primary electric current from the magneto was passed through the coils thereby energizing each individual coil selectively so that the secondary of each coil would be excited thereby causing a spark to jump across the spark gap of the respective plug.

The principal object of the present invention is to eliminate the necessity of providing more than a single coil thus materially reducing the expense of manufacture and simplifying the construction.

Another object of the invention is to provide a combination timer and distributor which is designed to complete the primary circuit through the coil and simultaneously complete the secondary circuit through the coil and one of the spark plugs.

With the above and other objects in view the invention consists in the novel construction, combination and arrangement of parts which will be fully set forth in the following specification, claimed and illustrated in the accompanying drawing in which:—

Figure 1 is a sectional view through this improved distributor illustrating diagrammatically the connections of the spark plugs, coil and generator.

Fig. 2 is an end elevation of the outer shell of the device.

Fig. 3 is an end view of the rotating element of the device.

Referring to the drawings in detail the numeral 5 designates the outer shell of this distributor which is substantially cone shaped and is provided at its reduced end with a concavity to receive the end of the

spring retaining arm 6 by means of which the shell is held in place. An annular series 55 of bushings 7 is secured in the shell 5 adjacent its larger end and mounted in said bushings are posts 8 on which the binding nuts 9 are threaded by means of which the cables 10 leading to the spark plugs may be connected thereto. The inner ends of the posts 8 are provided with contacts 11 the use of which will appear as the description proceeds.

Arranged near the reduced end of the shell 65 is a bushing 12 through which a post 13 extends and the outer end of this post is provided with a binding nut 14, while the inner end carries a spring pressed brush 15 for a purpose to be hereinafter more fully de- 70 scribed.

A binding screw 15' is connected to the shell and the inner terminal has secured thereto a spring 16 which is provided at its inner end with a brush 17. As illustrated 75 in the drawings the spring 16 lies in a longitudinal groove in the inner side of the casing 5. This spring extends toward the enlarged end of the casing and in such a manner as to dispose the brush 17 in position 80 to contact with the rotating element of the distributor which will be more fully hereinafter described.

The rotating element above referred to is designated by the numeral 18 and is secured to the cam shaft 19 in any preferred manner. A bushing 20 is provided at the extreme outer end of the rotating element and is adapted to be threaded on the cam shaft in the manner shown in the drawing 90 in order to establish good electrical communication between the cam shaft and bushing. Formed on the bushing and extending to the periphery of the rotating element are radial arms 21 which when the device is 95 assembled, contact with the brush 15, thereby completing the primary circuit from the generator through the coil. A collector ring 22 is carried by the rotating element 18 and is adapted to contact with the brush 17. A 100 distributing arm 23 is formed on the collector ring 22 and is arranged to successively engage the contacts 11 hereinbefore described.

In operation, it will be seen that when 105 the motor is set in operation, the cam shaft

19 will rotate the element 18 thereby causing the brush 23 to successively engage the contacts 11 at the same instant that the arms 21 contact with the brush 15. It will thus 5 be seen that the current passing from the generator 24 will enter the primary 25 of an induction coil 26 and thence pass through suitable connections to the post 13 from whence the current is carried through the 10 brush 15 and bushing 20 to the cam shaft 19 by means of which it is returned to the generator, thereby completing the primary circuit.

It will be obvious that the passing of the 15 current through the primary of the induction coil will excite the secondary 27, one terminal of which is grounded and the current generated in the secondary will pass through suitable connections to the post 15 20 and thence through the spring 16 and brush 17 to the collector ring 22. The arm 23 being at all times in electrical communication with the collector ring 22, it will be obvious that when said arm engages the 25 contacts 11, the current will flow through said arms and contacts and thence through the connections 10 to the spark plugs 28. In this way it will be seen that at the instant the spark plugs are connected to the 30 secondary 27 of the coil, the primary 25 of said coil will be energized.

The cap 5 is entirely constructed of insulating material and the same is provided with a radial flange B which extends in 35 parallel relation with the rotating element 18. The flange B is provided with an angular extension C, which operates to house the peripheral part of said rotating element and as illustrated, the latter is spaced from 40 the former. These parts are operatively associated so as to guard against passage of the current through the space between the periphery of said rotating element 18 and the guard or housing flange C. In this 45 manner the structure is insulated against accidental short circuits by sparks passing through the open side of said shell 5. The aforesaid rotating element 18 is also entirely formed of insulating material.

50 While in the foregoing there has been shown and described, the preferred embodiment of this invention, it is to be understood that certain minor changes in the details of construction, combination and arrangement of parts may be resorted to without departing from the spirit and scope of the invention as claimed.

What is claimed as new is:—

1. An ignition device comprising a disk-like element having a hub provided with a metallic bushing adapted for operative connection with one end of a cam shaft and serving to hold said disk-like elements in a position at right angles to the axis of said 65 cam shaft, a metallic collector ring secured

to said disk-like element and provided with a radial arm, said ring being concentric with the disk-like element, a cap housing said disk-like element, contact devices carried by said cap, said contact devices respectively adapted to co-act with said radial arm of the aforesaid collector ring and lying parallel to the axis of the bushing of said disk-like element, a contact element radiating from the cap and co-acting with 75 said metallic bushing, a contact brush co-acting with said metallic collector ring, the disk-like element formed of insulating material and associated with respect to the 80 walls of the cap to prevent leakage of the current past the effective sparking points between the metallic ring and its co-acting contact devices, all of said contact devices and said brush adapted to be operatively arranged in an ignition circuit. 85

2. An ignition device comprising a disk-like element having a hub provided with a metallic bushing adapted for operative connection with one end of a cam shaft and serving to hold said disk-like elements in 90 a position at right angles to the axis of said cam shaft, a metallic collector ring secured to said disk-like element and provided with a radial arm, said ring being concentric with the disk-like element, a cap housing 95 said disk-like element, contact devices carried by said cap, said contact devices respectively adapted to co-act with said radial arm of the aforesaid collector ring and lying parallel to the axis of the bushing of said disk-like element, a contact element radiating from the cap and co-acting with said metallic bushing, a contact brush co-acting with said metallic collector ring, the disk-like element formed of insulating material and associated with respect to the 100 walls of the cap to prevent leakage of the current past the effective sparking points between the metallic ring and its co-acting contact devices, all of said devices and said brush adapted to be operatively arranged in an ignition circuit, the said cap being slidable with relation to the disk like element, and means for holding said cap against sliding movement and in operative relation to 105 said element. 110

3. An ignition apparatus for use in connection with the cam shaft of an internal combustion engine, comprising a disk of insulating material adapted for fixed connection with the shaft and provided with a hub having means in contact therewith for establishing ground connection between the shaft and an ignition circuit, a cap adapted to extend over the end of the shaft and preferably around the disk-like element, a contact device carried by the cap and frictionally engageable with said means, a collector ring on the disk like element, a brush carried by the cap and in frictional contact 115 120 125 130

with said ring, a radial arm formed on said ring and frictional contact devices lying parallel to the cam shaft and carried by said cap and adapted for successive engagement with said arm, the disk-like element and said cap being each formed of insulating material and relatively disposed to prevent leakage of the current past the effective sparking points between the arm of said ring and its co-acting contact devices. ¹⁰
In testimony whereof I have affixed my signature.

CHASE KEHRER.
